US0D1049062S

(12) **United States Design Patent** (10) **Patent No.:** **US D1,049,062 S**
(45) **Date of Patent:** **** Oct. 29, 2024**

(54) **WIRELESS REMOTE CONTROL**

(71) Applicant: **ABL IP Holding, LLC**, Conyers, GA
(US)

(72) Inventor: **John R. Johnson**, Flowery Branch, GA
(US)

(73) Assignee: **ABL IP HOLDING, LLC**, Conyers,
GA (US)

(**) Term: **15 Years**

(21) Appl. No.: **29/866,434**

(22) Filed: **Sep. 12, 2022**

(51) **LOC (14) Cl.** **14-03**

(52) **U.S. Cl.**
USPC **D13/168; D13/173**

(58) **Field of Classification Search**

(57) **CLAIM**

The ornamental design for a wireless remote control as shown and described.

DESCRIPTION

FIG. 1 is a front view of a wireless remote control, showing the new design;

FIG. 2 is a rear view thereof;

FIG. 3 is a perspective top right view thereof;

FIG. 4 is a perspective top left view thereof;

FIG. 5 is a perspective bottom right view thereof; and,

FIG. 6 is a perspective bottom left view thereof.

The broken lines in the drawing depict portions of the wireless remote control and form no part of the claimed design.

1 Claim, 6 Drawing Sheets
